DESIGN FOR A DOLL

Henrietta Elliston, Chicago, Ill., assignor to Ziff-Davis Publishing Company, Chicago, Ill.

Application July 27, 1944, Serial No. 114,582

Term of patent 14 years

(Cl. D34—4)

To all whom it may concern:

Be it known that I, Henrietta Elliston, a citizen of the United States, residing at Chicago, in the county of Cook and State of Illinois, have invented a new, original, and ornamental Design for a Doll, of which the following is a specification, reference being had to the accompanying drawings, forming part thereof.

Fig. 1 is a front perspective view of a doll showing my new design.

Fig. 2 is a rear perspective of the doll.

I claim:

The ornamental design for a doll, as shown.

HENRIETTA ELLISTON.
